UNITED STATES PATENT OFFICE.

CLARENCE W. HAZELETT, OF LAKEWOOD, OHIO, ASSIGNOR TO NATIONAL CARBON COMPANY, INC., A CORPORATION OF NEW YORK.

DRY CELL.

1,331,762.

Specification of Letters Patent. Patented Feb. 24, 1920.

Application filed May 9, 1919. Serial No. 295,988.

To all whom it may concern:

Be it known that I, CLARENCE W. HAZELETT, a citizen of the United States, residing at Lakewood, in the county of Cuyahoga and State of Ohio, have invented a certain new and useful Improvement in Dry Cells, of which the following is a full, clear, and exact description.

This invention relates to dry cells.

- 10 It is well known that dry cells are made from zinc cans which contain an electrolyte mix tamped around a central carbon electrode with a paper or other bibulous lining between the mix and the can. When paper 15 is used as a bibulous lining it is the usual custom to use a lining that is considerably longer than the compacted mass of mix in the can, so that it may be folded over or otherwise crumpled into position on top of 20 the mix. To complete the cell a layer of sand is usually added on top of the folded-over portion of the lining, and then a seal 7, as molten pitch, is poured on top of the sand until it is substantially level with the 25 top of the can. With dry cells made as specified it is found that there is considerable trouble experienced through the corrosion of the zinc immediately below the layer of sand. The corrosion at this point is 30 much more rapid than in other portions of the cell, and frequently the top portion of the zinc will be entirely separated from the lower portion before the useful life of the cell would otherwise have terminated.
- 35 It has been found that the excessive corrosion of the zinc near the top is caused by the greater concentration of electrolyte in this neighborhood, due to the increased amount of electrolyte in the crumpled-over 40 portion of the lining. During the action of the cell the surface of the paper lining adjacent the zinc is depleted of electrolyte and this must be supplied by the diffusion of other electrolyte from the interior portion 45 of the lining and from the adjacent mix. Since there is a greater mass of the paper lining at the top due to the crumpled-over portion, the electrolyte will diffuse more rapidly to raise the concentration of the 50 electrolyte in the surface adjacent the zinc, than it will in the lower portions of the lining where there is only one thickness of lining. Consequently there results a higher concentration of electrolyte adjacent the 55 surface of the zinc where the lining is folded

over the top of the mix. The difference in concentration between the top of the zinc and the other portions causes continual electrolytic action that eventually dissolves away the zinc at the top.

It has also been found that the excessive corrosion near the top is caused in part by the good conducting path between the electrode and the zinc furnished by the bent-over portion of the lining which of course is 60 more or less saturated with good conducting electrolyte. In applying the paper lining to zinc cans it is usual to use such length of paper or pulpboard that the ends overlap in a vertical direction. This has 65 been found to cause corrosion of the zinc adjacent to this overlapping portion, which is due to the excess of electrolyte retained by the double thickness of lining, for substantially the same reason as previously described in connection with the bent-over portion at the top of the mix. My invention aims to overcome these disadvantages and the manner in which the result is accomplished will now be described, reference 70 being had to the drawings in which:

Figure 1 is a view of a sheet of paper containing my improvement.

Fig. 2 is a section of a battery can with the lining in position.

Fig. 3 is a section taken on the lines A—A of Fig. 1, a portion only of the lining being shown.

Fig. 4 is a view of a dry cell involving my improvement.

Referring to the drawings, I take a sheet of pulp or other form of paper board 1 and cut or saturate the top portion 3 and at least one side portion 2 with some material impervious to electrolyte and moisture, preferably one that is a non-conductor of electricity. Various materials may be used, but satisfactory ones are paraffin, tar and petroleum or other suitable oils.

The oils will be particularly serviceable 100 where it is desired to saturate the edges of the lining instead of applying an outside coating. However, by using such coating materials as paraffin and tar in hot condition, the lining edges may be saturated 105 therewith in the same way as when oils are used. In Fig. 3 the coating 2 is shown greatly exaggerated in thickness in relation to the lining 1. It will be understood that the top portion of the lining 3 will be sur- 110

rounded or saturated with the insulating material 4 in the same way as the edge portion 2.

After the linings are coated or impregnated in the manner specified, they are rolled up and placed inside the zinc can 5 with the edge portion 3 at the top of the can and the edge 2 overlapping the edge 6, the edge 6 being preferably located adjacent the zinc.

10 The mix 7 is tamped inside the lining 1 in any way, and the saturated or coated edge is bent over the top of the mix as shown in Fig. 4. The layer of sand 8 may be then added and the pitch or other seal 9 poured on top of the sand to complete the cell. A jacket is usually added to the outside of the zinc can, but this forms no part of the invention and it is not shown on the drawings.

With this construction it will be found 20 that the corrosion adjacent the pitch seal is no more energetic than in any other portion of the can. Also the corrosion adjacent to the overlapped portions 2 and 5 is the same as at any other point on the zinc. Consequently by the treatment of the bibulous lining in the way specified, the life of the cell is very materially increased.

Having described my invention, what I claim is:

30 1. In dry cells, a bibulous lining having a coating of impervious insulating material adjacent one edge.

2. In dry cells, a bibulous lining having a coating of impervious material on both sides adjacent to one edge and on said edge. 35

3. In dry cells, a bibulous lining having a portion thereof adjacent one edge impregnated with insulating material impervious to electrolyte or moisture.

4. In dry cells, a container electrode having an electrolyte mix therein, an electrode in said mix, a bibulous lining around the mix with the side edges overlapping each other, and insulating water-proof material in one of said overlapping edges. 40

5. In dry cells, a container electrode having an electrolyte mix therein, a central electrode in said mix, a bibulous lining around the mix, said lining having the top edge folded over the top of the mix and water-proof and insulating material in the overlapping portion of said lining. 50

6. In dry cells, a container electrode having an electrolyte mix therein, a second electrode in said mix, a bibulous lining around the mix with the side edges overlapping each other and with the top edge folded over the mix, and water-proof and insulating material in one of said overlapping edges and in said folded over edge. 55

In testimony whereof, I hereunto affix my signature.

C. W. HAZELETT.
